UNITED STATES PATENT OFFICE.

LAKE R. KNIGHT, OF COLUMBUS, OHIO, ASSIGNOR TO THE FEDERAL GLASS COMPANY, OF COLUMBUS, OHIO, A CORPORATION OF OHIO.

DESIGN FOR A GOBLET.

Application filed October 6, 1926. Serial No. 19,250. Term of patent 14 years.

To all whom it may concern:

Be it known that I, LAKE R. KNIGHT, a citizen of the United States, residing at Columbus, in the county of Franklin and State of Ohio, have invented a new, original, and ornamental Design for a Goblet, of which the following is the specification, reference being had to the accompanying drawing, forming a part hereof.

The figure is a perspective view of a goblet showing my new design.

I claim:

The ornamental design for a goblet, as shown.

LAKE R. KNIGHT.
